UNITED STATES PATENT OFFICE.

CHARLES F. MEILINK, OF TOLEDO, OHIO.

LOCKING DEVICE FOR SAFES.

Application filed January 13, 1922. Serial No. 528,909.

This invention relates to safes and vaults. This invention has utility when incorporated in sheet or wrought metal fireproof structures.

5 Referring to the drawings:

Fig. 1 is a perspective view, with parts broken away, of an embodiment of the invention in a fireproof safe;

Fig. 2 is a fragmentary section on the line

10 II—II, Fig. 1, with the doors closed;

Fig. 3 is a fragmentary section on the line III—III, Fig. 1, and

15 Figs. 4, 5, and 6, are enlarged detail views of the joint and bolt throw connection features.

A safe 1 is shown as having rearward angle frame member 2 and forward angle frame member 3, each of wrought metal. Carried by these main frames 2, 3, of the 20 structure is an outer housing 4. An inner housing 5 is spaced from this outer housing 4. Rods 6 between the frames 2, 3, are disposed to carry bars 7 for positioning this inner housing 5 as to the outer housing 4, in 25 which space an insulation packing may be disposed.

The forward side of this safe has an opening, and the space between the inner housing 5 and the outer housing 4 is completed by a 30 jamb member. This jamb member has a flange 8 engaging the inner housing 5. This flange 8 is integral with a rib 9 and in the extent toward the housing 4 this integral jamb has next a groove 10. From this groove 35 10 extends outwardly a riser portion having intermediate its extent a groove 11 extending in the plane of the opening of the safe instead of opening outward as does the groove 10. Beyond this groove 11 and still 40 further outward, is a groove 12. There then follows a ledge portion 13 as a seat adjacent a main flange mounting seat 14 of this jamb which terminates in a lip 15 against the inner side of the housing 4. This jamb is a 45 shape which may be produced by rolling in a rolling mill and may be conveniently spot welded or otherwise firmly attached to the inner side of the housing 5 and the frame 3. There is, accordingly, a wrought or sheet 50 metal structure housing completed by this endless jamb about the opening of the safe.

The safe 1 is closed by doors 16, 17, shown

as swingable upon hinges 18, carried by the front frame 3 of the safe. The door 16 is shown as having its side or edge remote from the hinge 18 as configured similarly to the jamb as to the parts 9, 10, 11, 12, 13. The three remaining sides of this door 16, and the four sides of the door 17, are shown as configured to oppose the configuration of the 60 jamb.

There is thus provided a shape which may be produced in a rolling mill. This shape as a safe door frame which comprises an inner seat 19 with a rib 20 therefrom to oppose the portion 8 of the jamb extends to a groove 21 for receiving the rib 9 of the jamb. From this groove 21 of the door frame there extends a rib 22 to enter the outwardly open groove 10 of the jamb. From this rib 22 there 70 extends a flare portion to a groove from which there is the riser portion outward to rib 23 for entering the groove 12 of the jamb. Outer terminal ledge 24 fits in the offset 13 and this door frame then terminates in a 75 flange against which the outer plate of the doors 16, 17, may be mounted. In order to get at the bolt work the inner plates 25, 26, of the doors 16, 17, are detachably mounted by means of bolts 27.

With the door 16 closed, the handle 28 may be operated to throw the bolts 29 into the groove 11 of the jamb, not only at the inside of the door 16 but also at the top and bottom thereof. With the handle 28 thus thrown into locking position for the door 16, bolt 30 is lowered so that the handle 31 may be operated for throwing the several bolts 29 from the door 17 into the groove 11 of the jamb at the hinge side of this door 17 as well 90 as the top and bottom thereof. Bolt 32, which has its way cleared by the bolt 30 moving downward, permits this operation and this bolt 32 moves into the groove 11, not of the jamb but in the door 16.

The structure of this disclosure not only embodies a rolled shape for the jamb of a configuration which may be produced in rolling mill operation, said rolled shape includes, without boring or drilling, a seat for the locking bolts, but this groove also serves as an air chamber. In the expansion under heat tests this chamber is sealed by the rolled door frame and serves as a retardant against

the conducting of heat inward toward the contents of the safe in the inner wall 5.

During the action of heat, should the safe be exposed to a severe fire, filling or packing 5 between the inner wall 5 and the outer wall 4 of the safe, may give off vapors or moisture which may pass through vent openings 34 into the groove 11 and thereby further assist in damming back any conducting 10 of heat from the outer side of the safe inward. The outer surfaces of these vents 34 may be varnished over so that the finished side of the safe is complete.

There is also considerable utility in the assembly of the safe as designed with this locking bolt groove continuous throughout the entire doorway opening or jamb. This feature is that there is only necessary lineup for the bolts in the plane of this groove 11, and 20 this single plane lineup is a very considerable saving in the speed of hanging the doors, for the bolts need only be aligned in the plane of the groove.

The action of heat in its expansion has 25 a tendency for the frame 3 to pull the jamb away from the door frame. As the ribs 22, 23, of the frame interfit in grooves 10, 12, of the jamb the sides of the grooves away 30 from the frame 3 are pulled against the corresponding sides of these ribs 22, 23. As the heat is more intense at the outer side there is accordingly first a sealing between the groove 12 and the rib 23, and in this pull action the ledge 24 slides directly as to the 35 facing ledge 13. If desired, packing strips 35, 36, may assist in isolating the chamber formed by the groove 11. The frame member 3 is of so much greater mass than the jamb and the door frame, that this member 40 3 is less readily heated. This frame member 3 accordingly serves to assist in holding the jamb against the door frame when heat expansion conditions arise.

The bolt throwing handles 28, 31, are 45 shown as mounted on spindles 37. Fixed fulcrum levers 29 are connected to the bolts 29 and are directly connected or are connected through link 29' to the cranks at the handles. The connections of the link, and 50 of the levers, are loose to permit of slight play. The cranks 38, 39, are loosely mounted on these spindles 37. The spindles 37 have anchored therewith key washers 40 as 55 held in position by lock nuts 41. Having threaded engagement with each lock washer 40 is a bolt 42 having reduced end 43 as a frangible extension to enter opening 44 in the respective cranks 38, 39. Accordingly, 60 should effort be made to force the bolts with the bolts held by the lock 45, this frangible extension 43 will give way. This is a safety device of considerable value against forcing entrance to this safe construction. This case, in so far as the subject-matter herein 65 is common, is a continuation in part of ap-

plicant's co-pending case which has developed into Patent 1,473,117 of Nov. 6, 1923.

What is claimed and it is desired to secure by Letters Patent is:

1. A safe provided with a door, a bolt for the door, a bolt actuator mounted for rotation, and a frangible connection eccentric of the actuator between the actuator and bolt. 70

2. A safe provided with a door, a bolt for the door, a crank with which the bolts are connected, an actuator spindle mounted for rotation, a frangible pin connection eccentric to the spindle between the spindle and crank, and a lock effective upon locking the door for holding the crank whereby attempt to 75 force the bolts by applying power to the spindle may break the pin and leave the bolts unthrown as held by the lock.

3. A safe having a polygonal opening, a jamb for the opening having a groove in the plane of the opening providing for the extent of said groove uniformity in the jamb cross-section, a polygonal door for registering with the opening and as so moved thereinto held engaged by the opening against angular shifting, a rock shaft carried by and extending to protrude from the front of the door, a bolt for the door, and a member pivotally connected to both the rock shaft and bolt and rockable relatively to each 80 thereof in shifting the bolt in the plane of the door to protrude marginally therefrom to engage the groove. 85

4. A safe door having an outer wall, a rock shaft through said wall, a pair of eccentrically disposed wrist pins carried by the shaft, and independent levers from said wrist pins, spaced fulcra for the levers, and bolts pivotally connected to the levers remote from the wrist pins. 90

5. A safe housing provided with an opening and seat means adjacent said opening, a closure for the opening, bolts carried by the closure, a shaft provided with a crank, and levers loosely connected to the crank and the bolts and fixed fulcra for the levers, said bolts and cranks being spaced along the levers from the fulcra whereby shaft rotation may be communicated through the levers for rocking the levers on their fulcra in effecting throwing and withdrawing of the bolts. 100

6. A bolt control mechanism embodying a rock shaft provided with a crank, a lever directly pivotally connected to the crank, a fulcrum for the lever, a bolt, and relative movement permitting connection means between the bolt and lever. 110

7. A bolt control mechanism embodying a shaft provided with a crank, a pair of parallel bolts, levers oppositely extending from said crank to the bolts, said levers being loosely connected to the bolts, and a fulcrum for each lever whereby rocking of the shaft is effective directly through one lever for 115 120 125 130

throwing one bolt, and is independently effective through the other lever for throwing the other bolt.

8. A bolt control mechanism embodying a rock shaft provided with a crank, a plurality of reciprocable bolts, and a rockable member from each bolt loosely connected to the bolt and the crank, one member movable rela-

tively to the other in bolt throw operation, whereby shifting of the crank from said shaft in its movement is direct for each bolt, and one bolt may not drag or bind to bring about any binding of another bolt or binding of the member to such other bolt.

In witness whereof I affix my signature.
CHARLES F. MEILINK.
